DEVICE FOR CONTROLLING THE TRANSMISSION OF POWER TO PUMPS

John C. Myers, Sperry, Okla., assignor of one-half to J. W. Scott Drilling Company, Tulsa, Okla., a corporation of Texas

Application April 26, 1939, Serial No. 270,096

18 Claims. (Cl. 103—23)

This invention relates to devices for controlling the transmission of power to pumps, and more particularly to the operation of pumps for lifting liquids, the object being to provide an efficient means for automatically stopping such pumps in response to the delivery of air, or other gaseous fluid to the pumps.

The capacity of many pumps is greater than that of more or less uncertain sources of liquid delivered to the pumps, and it is usually advisable to stop the pumps when the delivery of liquid is discontinued. For example, water or oil may be profitably pumped at intervals from many wells without exhausting the supply of liquid, but the intervals are usually uncertain, and the delivery of air or other gas to the pumps is likely to result in abrasion at the pump itself, and destructive stresses in the operating mechanism. By automatically stopping such pumps when the delivery of liquid is discontinued, the present invention positively eliminates the above mentioned hazard, and provides for safe and economical pumping of the liquid.

In the use of pumps for lifting oil from wells, a single operator is often required to attend to the pumping of many widely scattered wells. The operator usually begins by going from one well to another to start the pumps, or to inspect the pumping mechanism, and he then attends to other duties. Experience has very clearly shown that when the flow of oil to such pumps is discontinued, the pumps should be immediately stopped, but in actual practice the operator is unable to constantly observe the conditions at all of the wells, especially where the wells are widely separated and a number of pumps are operating at the same time. A similar condition arises when a person has only one well to contend with, as a single pump does not usually justify constant attention, and may be inspected only once or twice a day, perhaps to start the pump in the morning and stop it in the evening.

However, the operation of a pump after the flow of oil is discontinued results in several serious disadvantages, due to the delivery of air, or other gaseous fluid, to the pump. This condition produces a churning action which emulsifies the oil remaining in the well, and causes undue wear on the working parts of the pump, at the same time subjecting the pumping mechanism to destructive jerking which causes fatigue in the metal and is likely to break the sucker rods, thereby requiring difficult "fishing" to remove the broken rods.

The emulsified oil is a very troublesome product

not acceptable to pipe line companies, and excessive friction in the working barrel of the pump requires the operators to pull the long tubing, sucker rods and pump from the deep well, in order that the worn parts may be replaced. All of this involves a loss of production of oil during the period required for repairs, as well as increased operating costs, and the production of the objectionable emulsified oil for some time after the repaired pumping mechanism is restored and placed in service.

Another important advantage of the invention appears in the fact that it permits the ordinary simple pumping equipment to be safely used in pumping oil from very deep wells. Heretofore, such simple equipment comprising a reciprocable plunger near the bottom of the well, and sucker rods connecting the plunger to operating means above the ground, has been regarded as unsafe for pumping oil from very deep wells wherein continuous pumping would temporarily exhaust the wells. The destructive strains and abrasion due to delivery of air or gas to the plunger are likely to break the extremely long sucker rods, or cause other injury that would be impossible, or not feasible, to repair in a very deep well. The new device automatically stops the pumping mechanism in response to the delivery of air or gas to the pump plunger, thereby providing for safe and economical pumping of oil or other liquid from deep wells.

With the foregoing and other objects in view, the invention comprises the novel construction, combination and arrangement of parts herein-after more specifically described and shown in the accompanying drawings, which illustrate one form of the invention. However, it is to be understood that the invention comprehends changes, variations and modifications within the scope of the claims hereunto appended.

Fig. 1 is a diagrammatical view of a pumping apparatus embodying features of this invention.

Fig. 2 is a vertical section on a larger scale, with parts broken away, showing the pump plunger which operates in a cylindrical working barrel near the bottom of the well.

Fig. 3 is a section illustrating a stopping device adapted to discontinue the transmission of power to the plunger when air or other gaseous fluid is admitted to the plunger.

Fig. 4 is an enlarged section on the line 4—4 in Fig. 3 showing a latch member separated from a driven member.

Fig. 5 is a view similar to Fig. 4, showing the latch member engaged with the driven member.

to prevent continued downward movement of the pump plunger.

Fig. 6 is a diagrammatical view illustrating another form of the invention.

Fig. 7 is a detail view of the automatic stopping device shown in Fig. 6.

To understand the principle of the invention, one should bear in mind certain conditions existing in an ordinary pump. Therefore, without 10 in any way limiting the claims, I will briefly describe a few details of an oil well pump, and then refer to special conditions employed by me to control the automatic stopping device.

An ordinary simple pump of this kind, shown 15 in Fig. 1 and Fig. 2, comprises a cylindrical working barrel 10 located near the bottom of the well, and a string of tubing 11 through which the oil is lifted from said working barrel to a discharge pipe 12 above the surface of the ground. 20 A pump plunger 13 reciprocating in the working barrel 10 is usually operated by a string of sucker rods 14 extending upwardly from the plunger and connected to the operating mechanism above the ground. The bottom of the working barrel 10 may be equipped with a simple 25 check valve 15 to provide for the admission of oil to the working barrel. The reciprocating plunger 13 may be equipped with a traveling check valve 16 which opens during each downward stroke, as the plunger falls in the working barrel, and closes in response to each upward stroke when the plunger is lifted to discharge the oil. These movements of the plunger and check valves draw the oil from the surrounding 30 casing 17 into the working barrel 10 and thereafter lift the oil through the tubing 11 which extends upwardly from the working barrel.

Attention is now directed to the following conditions:

40 The weight to be lifted consists of the long string of sucker rods 14, the plunger 13, and the weight of the long column of liquid extending from the check valve 16 in the plunger to the discharge pipe 12 above the ground. However, during each normal downward stroke, the check valve 15 at the bottom of the working barrel is closed, and there is a column of oil extending from this bottom check valve to the upper end of the tubing 11. As a consequence, during each 45 normal downward stroke, the sucker rods and plunger merely fall in this column of liquid, and the weight is then limited to the actual weight of the sucker rods and plunger, minus the buoyant effect of the body of liquid, so that the falling weight during the normal downward stroke is 50 even less than the actual weight of the sucker rods and plunger.

When air or gas is drawn into the bottom of the working barrel 10, the weight to be lifted 55 during an upward stroke would again consist of the sucker rods and plunger, plus the weight of the tall column of oil supported on the plunger. However, if we assume that air or gas is drawn into the working barrel, and that there is no oil 60 between the check valve 16 in the plunger and the check valve 15 at the bottom of the working barrel, the weight during a downward stroke would be approximately the same as the weight to be lifted during an upward stroke. In this event 65 the check valve 16 in the plunger will remain closed, due to the downward pressure of the tall column of oil. Instead of merely falling in a buoyant liquid, the plunger is now forced downwardly by this very heavy column of liquid, and the air below the plunger will be readily com-

pressed by this high pressure, or forced backwardly through any leak at the bottom check valve 15.

I will hereinafter explain how I can take advantage of this abnormal weight to permit excessive downward movement of the plunger when a body of air or gas enters the pumping apparatus. Briefly stated, this excessive downward movement may be utilized to actuate the automatic stopping device, thereby stopping the 10 transmission of power to the pump. In the preferred form of the invention, the stopping device includes a spring which permits said excess downward movement of the plunger in response to the presence of gaseous fluid below the plunger, 15 and a stopping member operated by the transmission of movement from said plunger during said excess downward movement.

The operating means shown in Fig. 1 comprises a pump jack 18 having a pivotal support 19 and 20 connected by means of a cable 20 to a "polish rod" 21 at the upper end of the string of sucker rods 14. The means for operating said pump jack comprises a pull line 22 connected to the jack, and an eccentric 23 driven by a rotary power 25 shaft 24, said eccentric being surrounded by a band 25 connected to a pull rod 26.

To illustrate a suitable means for transmitting power from the pull rod 26, I have shown a hook 27 at one end of said pull rod, and a link 28 pivoted at 29. The hook is normally coupled to the link 28 as shown by full lines in Fig. 1 and Fig. 3, but under certain conditions, the hook will move to the left independently of the link, thereby permitting said link to drop by gravity to the 35 position shown by dotted lines. In other words, the link 28 is an uncoupling member adapted to release the pump plunger from the source of power.

To illustrate a means for stopping the pump 40 plunger, I have shown notches 30 forming abutments in the driven rod 22 (Fig. 3) and a latch member 31 adapted to enter either of said notches. Assuming that the latch member is located in one of said notches so as to stop the 45 pump plunger, the hook 27 may then move to the left with the result of releasing the uncoupling link 28 and discontinuing the transmission of power to the stopped plunger.

However, the link 28 is normally coupled to 50 the hook 27, and the latch member 31 is normally located in the elevated position shown in Figures 3 and 4 wherein its lower edge is spaced from the notched rod 22. The means for retaining said latch member 31 in its elevated position 55 comprises a sliding pin 32 adapted to lie within the enlarged lower portion of a slot 33 in the latch member, as shown in Figures 3 and 4, and a light spring 34 tending to retain said pin in this position. An operating handle 35 may be 60 connected to the latch member 31 for the purpose of lifting said latch member to the position shown in Fig. 3. I will hereinafter describe a means for moving the pin 32 to the left in Fig. 3, so as to locate the reduced portion 36 of said 65 pin at the slot 33, thereby releasing the latch and permitting it to fall onto the notched rod 22. Continued movement of said rod 22 will permit the latch 31 to enter one of the notches 30, so as to stop the rod 22, and release the uncoupling 70 link 28.

It is to be understood that when the pin 32 is moved to the left in Fig. 3, the latch 31 will immediately fall onto the notched rod 22 and thereby locate the reduced portion 36 of the

spring-pressed pin 32 in the slot 33. If the pin 32 is then released, the light spring 34 will force it against one side of the latch, but the friction due to such spring pressure will be overcome 5 by the weight of the latch 31 and its operating handle 35, so this friction will not prevent the latch from dropping into one of the notches 30. I have shown two of the notches 30, so that if the latch fails to enter one of the notches it will 10 have an opportunity to enter the second notch.

Attention is now directed to the devices shown in Fig. 3 for transmitting power from the link 28 to the rod 22. A driving device may be formed by a cap 37 screwed into a spring housing 38, said link 28 being connected to said cap, and the spring housing being provided with an abutment 39 engaged by a power-transmission spring 40. The notched rod 22 has a reduced end portion 41 extending through the spring 40 and provided with a spring seat 42 adjustably secured by a nut 43 screwed onto said reduced portion 41. The spring 40 is located directly between the spring seat 42 and the abutment 39 at the inner end of the spring housing, so the seat 42 can be adjusted to vary the initial compression of the spring. A guide cage 44 is adjustably screwed onto the rod 22 and slidably mounted in an outer housing 45, said guide cage having an abutment 46 at its inner end adapted to engage and operate the pin 32. However, under normal operating conditions, the stroke of said abutment 46 is not long enough to reach the pin 32, the extreme normal movement to the left being suggested by dotted lines in Fig. 3. As a 35 factor of safety, the outer housing 45 is provided with a bumper plate 47 adapted to be engaged by the abutment 46.

To understand the operation of the automatic stopping device shown in Figures 1 to 5, inclusive, 40 it is necessary to carefully consider a number of different conditions. The spring housing 38 and its cap 37 are to be regarded as driving members, while the notched rod 22 and the abutment 46 near one end of said rod are regarded as driven members, the driving power being transmitted 45 through the spring 40. Also bear in mind that during each lifting stroke of the pump plunger there is a severe load consisting of the weight of the sucker rods and pump plunger, plus the 50 weight of the very tall column of liquid to be lifted. This load is great enough to compress the power transmission spring 40 in response to each lifting stroke of the pump plunger, said spring being retained under compression 55 throughout each lifting stroke.

However, during each downward stroke of the pump plunger, the traveling check valve 16 in the plunger is open while the check valve 15 at the bottom of the working barrel 10 is closed, and there is a column of oil extending from this bottom check valve to the surface of the ground. As a consequence, during each normal downward stroke, the sucker rods and plunger merely fall in this body of liquid, and the weight is then 60 limited to the actual weight of the sucker rods and plunger, minus the buoyant effect of the body of liquid, so the falling weight during the normal downward stroke is even less than the actual weight of the sucker rods and plunger.

The compression of the spring 40 is, therefore, 65 relieved during each normal downward stroke of the plunger. Of course, the falling weight may be great enough to slightly compress the spring, but in any event, the compression is considerably less than the compression which occurs

during a lifting stroke. During the normal downward movements of the plunger, while the plunger and sucker rods are merely falling in the tall column of liquid, this falling weight pulls the notched rod 22 to the left in Fig. 3, and when 5 the plunger reaches the end of its normal downward stroke, the abutment 46 carried by said rod 22 may be located in the position shown by dotted lines in Fig. 3, adjacent to but separated from the pin 32. Under these normal operating 10 conditions, said abutment 46 does not move far enough to release the latch 31.

Assuming now that the delivery of liquid to the pump plunger is discontinued, and that air or other gas is drawn into the lower portion of 15 the working barrel beneath the plunger. During an upward stroke, the spring 40 will be compressed as usual, due to the weight of the plunger and sucker rods, plus the weight of the tall column of liquid above the plunger. However, 20 an abnormal condition will appear during the next downward stroke. There is a body of air or gas below the plunger and a very heavy column of liquid above the plunger, exerting downward pressure on the check valve 16 in the 25 plunger. Under these conditions, the weight during the downward stroke may be approximately the same as the weight to be lifted during an upward stroke. Therefore, the spring 40 will be retained under compression, and as a 30 consequence, the abutment 46 (Fig. 3) carried by the rod 22 will then be separated from the abutment 39 at one end of the spring housing. This condition will exist at the beginning of the 35 downward stroke of the pump plunger, and as the plunger continues its downward movement, the abutment 46 will engage and operate the pin 32 so as to release the latch 31, which then falls onto the rod 22. At this time the pump plunger is located in a relatively low position, due to the 40 excess downward motion permitted by compression of the spring 40.

During the next upward stroke of the pump plunger, the notches in the rod 22 idly pass the 45 released latch 31, but during the following downward stroke of the plunger, the latch 31 falls into a notch 30 so as to stop the plunger at an intermediate stage of its downward movement. The driving members 37 and 38 continue in motion to relieve the compression of the spring 40, which 50 forces the abutment 39 onto the abutment 46. Thereupon, the hook 27 (Fig. 3) continues in motion independently of the stopped driving members 37 and 38, so as to release the uncoupling link 28. 55

The transmission of power to the pump plunger is thus discontinued in response to excessive downward movement of the plunger. However, the stopping effect is delayed until the next downward stroke of the plunger, and said plunger is 60 then stopped in an intermediate position. Therefore, the link 28 can be readily coupled to the hook 27 whenever the operator desires to continue the pumping.

It is to be understood that during the operation 65 of the pump, uniform strokes are transmitted from the source of power to the driving members 37 and 38 (Fig. 3), but these strokes are longer than the uniform strokes normally delivered to the driven members 22 and 46. Immediately before each normal upward stroke of the plunger, the spring 40 is compressed, due to the weight of the column of liquid above the plunger, and at this initial stage, the driving members 37 and 38 move independently of the driven mem. 70 75

bers 22 and 46. A similar condition exists at the beginning of each normal downward stroke, when the plunger is relieved of its load and permitted to fall in the trapped column of liquid, at which time the spring 40 expands and permits the driving members 37 and 38 to move independently of the driven members 22 and 46.

However, when the spring 40 is retained under compression during a downward stroke of the plunger, due to the presence of air or gas below the plunger, the relatively long stroke of the plunger is transmitted to the notched rod 22, so as to engage the traveling stopping member (abutment 46) with the normally stationary stopping member (pin 32). This action eventually stops the plunger and disconnects it from the source of power. It will be observed that the stopping members are operated by the pump plunger which transmits its excess movement to the rod 22. This rod is driven by the source of power during each upward stroke of the plunger, but during each downward stroke, said rod is driven by the plunger.

Fig. 6 and Fig. 7 illustrate a simple form of the invention wherein the "polish rod" 21' at the upper end of the string of sucker rods is driven through the medium of a beam 48 pivotally supported at 49 and connected by means of a pitman 50 to a crank 51 actuated by a motor 52. This motor may be regarded as an internal combustion motor, or an electric motor, controlled by an electric circuit including wires 53 and a switch 54, said switch having an operating arm 55 movable to stop the motor. An arcuate member 56, extending from the beam 48, is connected by means of cables 57 to an outer housing 58. A bolt 59, extending from said housing, is provided with an adjusting nut 60 seated on said housing, and a head 61 at its lower end to receive a spring seat 62. A spring housing 63 surrounds the bolt 59, and a spring 64 is interposed between the seat 62 and an abutment 65 at the upper end of said spring housing. The nut 60 can be adjusted to vary the initial compression of the spring 64. The "polish rod" 21' is connected to a cap 66 carried by the lower end of the spring housing. A traveling stopping member 67 is adjustably clamped onto the "polish rod" 21' so as to engage the normally stationary operating arm 55 in response to excessive downward movement of the "polish rod".

In the form shown by Fig. 6 and Fig. 7, the driving members include the outer housing 58 and the bolt 59. Uniform strokes are imparted to these driving members in response to the rotary movement of the crank 51, regardless of conditions in the well.

The companion driven members include the spring housing 63, the "polish rod" 21' and the traveling stopping member 67 carried by said "polish rod". These driven members are pulled upwardly by the source of power, but they move downwardly in response to downward movements of the pump plunger and sucker rods.

At the beginning of each upward stroke of the driving members, the spring 64 is compressed due to the weight of the tall column of liquid supported on the pump plunger, and this compression is maintained throughout the upward stroke. However, at the beginning of each normal downward stroke the compression is relieved, as the load is then reduced to the weight of the pump plunger and sucker rods, minus the buoyant effect of the trapped column of liquid.

As a consequence, under normal operating con-

ditions, the strokes of the driven members 63, 21' and 67 are uniform, but shorter than the uniform strokes of the driving members 58 and 59. An abnormal condition exists when air or gas is drawn into the bottom of working barrel, so as to replace the liquid beneath the plunger. When this occurs, the spring 64 is subjected to the usual compression during an upward stroke, but the compression is continued during the next downward stroke, due to the weight of the tall column of liquid exerted against the check valve in the plunger. For reasons previously given in referring to Figures 1 to 5, the plunger will then make an excessive downward stroke and carry with it the "polish rod" 21' and stopping member 67, so as to move said stopping member into engagement with the arm 55 of the stopping switch 54, thereby discontinuing the transmission of power to the pump plunger.

In the form shown by Fig. 6 and Fig. 7, the plunger may be stopped while in an abnormally low position, but it is not disconnected from the source of power so the pumping operation can be resumed after any desired interval by merely restoring the switch arm 55. In the form shown by Figures 1 to 5, the stopping impulse is given during an excessive downward stroke, but the transmission of power is continued until the driving members are conveniently located in intermediate positions where they can be readily disconnected from and thereafter coupled to the source of power.

In addition to the various important advantages gained by automatically stopping a pump in response to the delivery of air or gas to the pumping elements, the specific devices herein shown tend to relieve the shocks which occur under ordinary pumping conditions. It will be observed that the usual conditions include rapid changes in the load at the beginning of each stroke, and that such changes tend to strain or distort the power lines. Such distortion and strains are relieved by the power transmission spring 40 or 64, which serves as a shock absorber during the changes in the load on the plunger. Another peculiar action of the spring appears in its ability to yield in response to the maximum load while performing its function as a shock absorber, without in any way affecting the automatic stopping device, but when air or gas is delivered to the plunger, the same maximum load, or even a lighter load, will result in operation of the stopping device.

I claim:

1. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, a source of power to operate the plunger, a driving member actuated by said source of power, and a driven member connected to said pump plunger, the improvement comprising a stopping device including a stopping member carried by said driven member to discontinue the transmission of power to the plunger when a gaseous fluid is delivered to said plunger, said stopping device also including a yieldable shock absorber through which the lifting power is transmitted from said driving member to said driven member.

2. In an apparatus for lifting liquid from a

well provided with a pump plunger movable upwardly to lift the liquid and movable downwardly in the body of liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, and a source of power to operate said plunger, the improvement which comprises a stopping device to discontinue the transmission of power to the plunger when a gaseous fluid is transmitted to said plunger, said stopping device including a spring permitting excess downward movement of the plunger in response to the presence of gaseous fluid below the plunger, and a stopping member operated by said plunger during said excess downward movement.

3. In an apparatus for lifting liquid from a well provided with a pump plunger movable upwardly to lift the liquid and movable downwardly in the body of liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, and a source of power to operate said plunger, the improvement which comprises a stopping device to discontinue the transmission of power to the plunger when a gaseous fluid is transmitted to said plunger, said stopping device including a spring through which the lifting power is transmitted to said plunger, said spring permitting excess downward movement of the plunger in response to the presence of gaseous fluid below the plunger, a traveling stopping member operated by said plunger, and a normally stationary stopping member driven by said traveling member during said excess downward movement of the plunger.

4. In an apparatus for lifting liquid from a well provided with a pump plunger movable upwardly to lift the liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, and a source of power to lift the plunger, said plunger being free to move downwardly in the liquid, the improvement comprising a stopping device to discontinue the transmission of power to the plunger when a gaseous fluid is delivered to said plunger, said stopping device including a spring through which the lifting power is transmitted from said source of power to said plunger, so as to permit excess downward movement of the plunger on said gaseous fluid, and a stopping member movable by said plunger to actuate said stopping device in response to excess downward movement of the plunger.

5. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, a source of power to operate the plunger, a driving member actuated by said source of power, and a driven member connected to said

pump plunger, the improvement comprising a stopping device to discontinue the transmission of power to the plunger when a gaseous fluid is delivered to said plunger, said stopping device including a power transmission spring through which the lifting power is transmitted from said driving member to said driven member, and a stopping member carried by said driven member to actuate said stopping device.

6. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, and a source of power to operate the plunger, the improvement comprising a stopping device to discontinue the transmission of power to the plunger when a gaseous fluid is delivered to said plunger, said stopping device including a spring through which the lifting power is transmitted from said source of power to said plunger, the strokes of said source of power being uniform and longer than the normal strokes of said plunger, said spring being yieldable in response to the lifting strokes of said source of power and plunger and relatively free during the normal return strokes, so as to avoid excess movement of the plunger during said normal return strokes, and a stopping member driven by said plunger to actuate the stopping device in response to excess movement of said plunger.

7. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, a source of power to operate the plunger, a driving member actuated by said source of power, and a driven member connected to said pump plunger, the improvement comprising a stopping device to discontinue the transmission of power to the plunger when a gaseous fluid is delivered to said plunger, said stopping device including a spring through which the lifting power is transmitted from said driving member to said driven member, the strokes of said driving member being uniform and longer than the normal strokes of said driven member, said spring being yieldable in response to the lifting strokes of said driving member and plunger and relatively free during the normal return strokes, so as to avoid excess movement of the plunger and driven member during said normal return strokes, and a stopping member carried by said driven member to actuate the stopping device in response to movements of said driven member.

8. In an apparatus for lifting liquid from a well provided with a pump plunger movable upwardly to lift the liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, a driving member actuated by said source of power, and a driven member connected to said pump plunger, the improvement comprising a stopping device to discontinue the transmission

of power to the plunger when a gaseous fluid is delivered to said plunger, said stopping device including a spring through which the lifting power is transmitted from said driving member 5 to said driven member so as to permit excess downward movement of said plunger on said gaseous fluid, the strokes of said driving member being uniform and longer than the normal strokes of said driven member, said spring being yieldable 10 in response to the lifting strokes of said driving member and plunger and relatively free during the normal return strokes, so as to avoid excess downward movement of the plunger during said normal return strokes, and a stopping member carried by said driven member to actuate the stopping device in response to excess downward movement of said plunger.

9. In an apparatus for lifting liquid from a well provided with a pump plunger movable upwardly 20 to lift the liquid and movable downwardly in the body of liquid, a cylinder in which the plunger reciprocates, said cylinder having an inlet through which liquid is delivered to the plunger under normal pumping conditions, said inlet providing 25 for the admission of gaseous fluid to the cylinder and plunger when the flow of liquid is interrupted, a source of power to operate the plunger, a driving member actuated by said source of power, and a driven member connected to said 30 pump plunger, the improvement comprising a stopping device to discontinue the transmission of power to the plunger when a gaseous fluid is delivered to said plunger, said stopping device including a power-transmission spring through 35 which the lifting power is transmitted from said driving member to said driven member, said transmission spring being yieldable to permit an excess downward stroke of the plunger in response to the presence of gaseous fluid below the 40 plunger and also yieldable in response to the lifting strokes of said driving member and plunger but relatively free during the normal downward strokes, so as to avoid excess movement of the plunger during said normal downward strokes, 45 and a stopping member carried by said driven member to actuate said stopping device in response to excess downward movement of the plunger.

10. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the 50 admission of gaseous fluid to the cylinder and plunger when the flow of liquid is interrupted, a source of power to operate the plunger, a driving member actuated by said source of power, and a driven member connected to said pump plunger, the improvement comprising a stopping device to discontinue the transmission of power to the plunger when a gaseous fluid is delivered to said plunger, said stopping device including a compression spring through which the lifting 55 power is transmitted from said driving member to said driven member, the strokes of said driving member being uniform and longer than the normal strokes of said driven member, said compression spring being yieldable in response to the lifting strokes of said driving member and plunger and relatively free to expand during the normal return strokes, so as to avoid excess movement of the plunger and driven member during 60 said normal return strokes, and a stopping member carried by said driven member to actuate said 65

stopping device in response to compression of said spring during the return strokes of the plunger.

11. In an apparatus for lifting liquid from a well provided with a pump plunger movable upwardly to lift the liquid and movable downwardly in the body of liquid, a cylinder in which the plunger reciprocates, said cylinder having an inlet through which liquid is delivered to the plunger under normal pumping conditions, said inlet 10 providing for the admission of gaseous fluid to the cylinder and plunger when the flow of liquid is interrupted, and a source of power to operate said plunger, the improvement which comprises an electric switch to discontinue the transmission of power to the plunger when a gaseous fluid is transmitted to said plunger, a spring permitting 15 excess downward movement of the plunger in response to the presence of gaseous fluid below the plunger, and a traveling stopping member operated by said plunger, said electric switch having an operating member engaged by said traveling stopping member during said excess downward movement of the plunger.

12. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the 30 admission of gaseous fluid to the cylinder and plunger when the flow of liquid is interrupted, a source of power to operate the plunger, a driving member actuated by said source of power, and a driven member connected to said pump 35 plunger, the improvement comprising a stopping device including an electric switch to discontinue the transmission of power to the plunger when a gaseous fluid is delivered to said plunger, said stopping device also including a spring through 40 which the lifting power is transmitted from said driving member to said driven member, the strokes of said driving member being uniform and longer than the normal strokes of said driven member, said spring being yieldable in response 45 to the lifting strokes of said driving member and plunger and relatively free during the normal return strokes, so as to avoid excess movement of the plunger and driven member during said normal return strokes, and a stopping member carried by said driven member to actuate said electric switch in response to excess movement of 50 said driven member.

13. In an apparatus for lifting liquid from a well provided with a pump plunger movable upwardly to lift the liquid and movable downwardly in the body of liquid, a cylinder in which the plunger reciprocates, said cylinder having an inlet through which liquid is delivered to the plunger under normal pumping conditions, said inlet 60 providing for the admission of gaseous fluid to the cylinder and plunger when the flow of liquid is interrupted, a source of power to operate the plunger, a driving member actuated by said source of power, and a driven member connected to said pump plunger, the improvement comprising a stopping device including an electric switch to discontinue the transmission of power to the plunger when a gaseous fluid is delivered to said plunger, said stopping device also including a power-transmission spring through which the lifting 65 power is transmitted from said driving member to said driven member, said transmission spring being yieldable to permit an excess downward stroke of the plunger in response to 70

- the presence of gaseous fluid below the plunger and also yieldable in response to the lifting strokes of said driving member and plunger but relatively free during the normal downward strokes, so as to avoid excess movement of the plunger during said normal downward strokes, and a switch-operating member carried by said driven member to actuate said electric switch in response to excess downward movement of the plunger.
10. 14. In an apparatus for lifting liquid from a well provided with a pump plunger movable upwardly to lift the liquid and movable downwardly in the body of liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, and a source of power to operate said plunger, the improvement which comprises a stopping device to discontinue the transmission of power to the plunger when a gaseous fluid is transmitted to said plunger, said stopping device including a spring permitting an excess downward stroke of the plunger in response to the presence of gaseous fluid below the plunger, a stopping member released by said plunger during said excess downward stroke, said stopping member being adapted to stop said plunger at an intermediate stage of the next downward stroke, and an uncoupling member to disconnect the stopped plunger from the source of power.
15. 15. In an apparatus for lifting liquid from a well provided with a pump plunger movable upwardly to lift the liquid and movable downwardly in the body of liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, a source of power to operate said plunger, a driving member actuated by said source of power, and a driven member connected to said driving member, the improvement which comprises a stopping device to discontinue the transmission of power to the plunger when a gaseous fluid is transmitted to said plunger, said stopping device including a spring between said driving member and driven member permitting an excess downward stroke of the plunger in response to the presence of gaseous fluid below the plunger, a stopping member released by said driven member during said excess downward stroke, said stopping member being adapted to stop said driven member and plunger at an intermediate stage of the next downward stroke, and an uncoupling device to disconnect the stopped plunger from the source of power, said uncoupling device being located between said spring and the source of power and operable in response to a reduction in the pressure of said spring.
20. 16. In an apparatus for lifting liquid from a well provided with a pump plunger movable upwardly to lift the liquid and movable downwardly in the body of liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, a source of power to operate the plunger, a driving member actuated by said source of power, and a driven member connected to said pump plunger, the improvement comprising a stopping device to discontinue the transmission of power to the plunger when a gaseous fluid is delivered to said plunger, said stopping device including a power-transmission spring through which the lifting power is transmitted from said driving member to said driven member, said transmission spring being yieldable to permit an excess downward stroke of the plunger in response to the presence of gaseous fluid below the plunger and also yieldable in response to the lifting strokes of said driving member and plunger but relatively free during the normal downward strokes, so as to avoid excess movement of the plunger during said normal downward strokes, a stopping member carried by said driven member to stop said driven member in response to excess downward movement of the plunger, said driving member being movable independently of the stopped driven member in response to the pressure of said power-transmission spring, and an uncoupling member released in response to the last mentioned movement of said driving member so as to release the driving member from the source of power.
25. 17. In an apparatus for lifting liquid from a well provided with a pump plunger movable upwardly to lift the liquid and movable downwardly in the body of liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, a source of power to operate the plunger, a driving member actuated by said source of power, and a driven member connected to said pump plunger, the improvement comprising a stopping device to discontinue the transmission of power to the plunger when a gaseous fluid is delivered to said plunger, said stopping device including a power-transmission spring through which the lifting power is transmitted from said driving member to said driven member, said transmission spring being yieldable to permit an excess downward stroke of the plunger in response to the presence of gaseous fluid below the plunger and also yieldable in response to the lifting strokes of said driving member and plunger but relatively free during the normal downward strokes, so as to avoid excess movement of the plunger during said normal downward strokes, a stopping member released by said driven member in response to excess downward movement of the plunger, said stopping member being adapted to stop said driven member and plunger at an intermediate stage of the next downward stroke, and an uncoupling device to release said driving member from the source of power, said uncoupling device being located between said spring and the source of power and free to release said driving member when the pressure of said spring is reduced.
30. 18. In an apparatus for lifting liquid from a well provided with a pump plunger to lift the liquid, a cylinder in which the plunger reciprocates, said cylinder having an inlet through which liquid is delivered to the plunger under normal pumping conditions, said inlet providing for the admission of gaseous fluid to the cylinder and plunger when the flow of liquid is interrupted, a source of power to operate the plunger, a driving member actuated by said source of power,

and a driven member connected to said pump plunger, the improvement comprising a stopping device to discontinue the transmission of power to the plunger when a gaseous fluid is delivered to said plunger, said stopping device including a compression spring through which the lifting power is transmitted from said driving member to said driven member, the strokes of said driving member being uniform and longer than the normal strokes of said driven member, said compression spring being yieldable in response to the lifting strokes of said driving member and plunger and relatively free to expand during the

normal return strokes, so as to avoid excess movement of the plunger and driven member during said normal return strokes, a coupling device located between said spring and the source of power, and connecting said driving member to the source of power, said coupling device including an uncoupling member to disconnect said driving member from the source of power, and a stopping member carried by said driven member to release said uncoupling member in response to compression of said spring during the return strokes of the plunger. 5 10

JOHN C. MYERS.

CERTIFICATE OF CORRECTION.

Patent No. 2,202,504.

May 28, 1940.

JOHN C. MYERS.

It is hereby certified that error appears in the above numbered patent requiring correction as follows: In the grant, line 15, for "and and J. W. Scott" read --and J. W. Scott--; and that the said Letters Patent should be read with this correction therein that the same may conform to the record of the case in the Patent Office.

Signed and sealed this 9th day of July, A. D. 1940.

(Seal)

Henry Van Arsdale,
Acting Commissioner of Patents.
